DESIGN FOR A FLAG.

Application filed April 23, 1923. Serial No. 5,906. Term of patent 7 years.

To all whom it may concern:

Be it known that I, JAMES K. DUFFY, a citizen of the United States, residing at New York, in the county of New York and State of New York, have invented a certain new, original, and ornamental Design for Flags, of which the following is a specification, reference being had to the accompanying drawing, forming part thereof.

The figure is an elevational view of a flag, showing my new design.

The novel design of this invention com-

prises essentially a rectangular field 1 having in the center an elliptical figure 2 of contrasting color containing the capital letters C. F., and the ground outside carrying contrasting diagonal stripes 3. The design is shown as being lined for red for the central figure 2, green for the stripes 3, and white for the field 1.

I claim:

The ornamental design for a flag substantially as shown and described.

JAMES KING DUFFY.
